DIVIDER FOR MOWING MACHINES

Filed Jan. 21, 1928

UNITED STATES PATENT OFFICE

WILLIAM C. JACKSON, OF WAPATO, WASHINGTON

DIVIDER FOR MOWING MACHINES

Application filed January 21, 1928. Serial No. 248,309.

This invention relates to dividers for mowing machines and has as one of its objects to provide a divider that is adaptable to divider shoes without alteration thereof.

Another object of the invention is to provide a divider that may be easily and rigidly secured to the divider shoe.

A further object of the invention is to provide a divider that is adjustable and that is rigid in all its adjustments.

A further object of the invention is to provide a divider that is cheap to manufacture and that is highly efficient in operation.

With these and other objects in view reference is now had to the accompanying drawings in which

Fig. 1 is a plan view of a divider shoe;

Fig. 2 is a side elevation thereof showing one of the divider rods;

Fig. 3 is a side elevation of a fragment of the divider shoe showing another position of the rod;

Fig. 4 is a plan view of the shoe and rod (reduced);

Fig. 5 is a side elevation of a fragment of a divider shoe and divider board; and

Fig. 6 is a similar view to Fig. 3 showing a modified form of securing means for the divider rod.

Having reference to the drawings like numerals refer to like parts throughout the several views and the numeral 1 refers to a dividing shoe, such as are used ordinarily on mowing machines and the like, the dividing shoe consisting of a frame 2 having a lateral inclination and an extended plate 3 curved inward from the direction of travel, and adapted to carry a pivotally mounted dividing board 4 flexibly mounted thereon by means of a bolt 5, upon which is mounted a tension spring 6 wherewith to normally maintain the board in continuation of the plate 3 and to permit the rise and fall of the outer end of the board 4 during operation.

A tread 7 is hinged to the bottom 8 of the shoe by means of a hook hinge 9 positioned at the forward end of the tread and its rearward end is adjustably supported by an angle piece 10 that is extended laterally and bent upright to bring the tread in the line of travel, and

to provide means to adjustably secure the tread in a desired position.

For the purpose of securing a housing 11 is formed integral with the frame, and is slotted, as at 12, to receive a bolt 13, the head 14 of which is secured within the housing in the usual manner, while a nut 15 engages the bolt to secure the angle piece against the housing 11 in the adjusted position.

The frame has further a pointed toe 16, with a top rib 17, extending from the toe over the top of the frame to terminate in a shoulder 18 positioned above and slightly to the rear of the housing 11.

The housing contains the usual sickle bar 19, seat 20, and blade guide 21, about which is a lower rib 22.

The extended plate 3, as above mentioned, curves inward laterally and contains a hole 23 that was originally intended to receive the above mentioned bolt 5, and through this hole without further alteration other than the removal of the said bolt 5, is inserted a rod bolt 24 for a purpose to be explained.

The dividing rod 24 consists of a single rod 75 adapted for adjustable securing to the extended plate 3 of the shoe, and comprises a straight extension 25 terminating rearwardly in a lateral curvature 26.

The straight extension continues forward 80 and terminates at the forward end 27 in a slotted plate 28 formed integral with and perpendicular to the rod 24, and may comprise the alternative forms shown in Fig. 3 and Fig. 6, that shown in Fig. 3 being my 85 preferred form and consisting of a depending plate 28 with the top edge of the plate forming a face 29 adapted to bear against the top rib 17, with the face bearing portion projecting forward in a lug 30, the latter being 90 adapted to rest in contact with the top of the housing 11 under certain conditions of securing, and still being positioned in a manner to permit of adjustment of the rod, 95 while the slot 31 in the plate is elongated to receive the bolt 23, with which the rod is secured to the extended plate 3, and about which bolt the rod may be rotated for adjustment, and by means of the elongated slot to rigidly 100

brace the rod when secured with the face 29 contacting the shoulder 18.

The modified form has its plate extended upward and its upper edge provides the face 5 29 wherewith to provide bracing for the rod similar to that of my preferred form.

While the slot 31 in my preferred form is shown straight it is obvious that it may be curved if desired, and while the slot shown 10 in the modified form is curved it is also obvious that it may be straight, the arrangement of the slot being such as may best bring the face in contact with the top rib 17 when the nut 32 is tightened on the bolt 23, thus 15 securing the rod rigidly.

In use, the dividing rod is attached securely to the dividing shoe by placing the plate against the extended plate and inserting the bolt 23 through the hole in the extended plate and the slot 31, the nut 32 is then 20 threadedly attached to the bolt and screwed nearly to place.

The rod is now raised to the proper position, according to the height of grain to cut, 25 and the plate is then raised until the face 29 abuts the top rib 17 when the nut is forced tight against the plate 28 and the whole is adjustably secured to the shoe.

As the mower moves over the hay or grain 30 the dividing rod forces the cut hay away from the standing hay to provide a path for the horses on the next succeeding round.

By means of the straight extension the laterally curved portion of the rod is brought 35 further to the rear than other dividing rods and thus is capable of handling larger and heavier hay with great efficiency the smaller and lighter hay being of relatively less importance when laying in the path of the 40 mower.

Having thus described my invention, I claim—

1. In a divider, the combination with a 45 dividing shoe having an outwardly projecting top rib, terminating in a shoulder, a projecting housing positioned beneath said rib, and an inwardly curved extended portion forming the rear end of said shoe, and adapted normally to receive pivotally a divider board, and having the pivotal mounting positioned rearwardly of said rib and said housing, of a dividing rod terminating at one end in a lateral inward curvature and at its 50 other end in a securing means consisting of a slotted plate formed integral with and perpendicular to said dividing rod, and positioned to engage the shoulder of said top rib, and having a lug extended forward of said 55 slotted plate for engagement with said housing, said shoulder and said housing forming braces therefor, and means to pivotally secure said slotted plate to the original pivotal mounting of said extended portion of the 60 shoe.

2. In a divider, the combination with a dividing shoe having an outwardly projecting top rib, terminating in a shoulder, a projecting housing positioned beneath said rib, and an inwardly curved extended portion forming the rear end of said shoe, and adapted normally to receive pivotally a divider board, and having the pivotal mounting positioned rearwardly of said rib and said housing, of a dividing rod terminating at its forward end in a securing means consisting of a slotted plate formed integral with and perpendicular to said dividing rod, and positioned to engage the shoulder of said top rib, and having a lug extended forward of 75 said slotted plate for engagement with said housing, said shoulder and said housing forming braces therefor, and means to pivotally secure said slotted plate to the original pivotal mounting of said extended portion 80 of the shoe.

In testimony whereof I affix my signature.

WILLIAM C. JACKSON.
